UNITED STATES PATENT OFFICE.

HUGO HARALD WURFSCHMIDT, OF VIENNA, AUSTRIA-HUNGARY.

FOUNTAIN-BRUSH.

1,082,839.

Specification of Letters Patent. Patented Dec. 30, 1913.

Application filed October 2, 1911. Serial No. 652,434.

To all whom it may concern:

Be it known that I, HUGO HARALD WURFSCHMIDT, a subject of the Emperor of Germany, residing at Baumannstrasse 8, Vienna, III, in the Empire of Austria-Hungary, have invented a new and useful Improved Fountain-Brush, of which the following is a specification.

This invention relates to brushes or the like for wet brushing in which the moistening agent is supplied to the bristles or the like from the body of the brush (which is made hollow so as to form a liquid reservoir) through an obturating member adapted to be opened from the exterior.

The invention consists in the arrangement of a force-pump in the body of the brush (which is formed as the reservoir), the cylinder of this pump communicating with the reservoir and being closed on one side by an obturating member and on the other side by the piston of the pump in such a manner that when the piston is depressed the obturating member is opened and the moistening agent discharged from the cylinder under pressure by the action of the piston. It is advantageous to make the cylinder of such a length that it extends entirely through the body of the brush as this facilitates obtaining a perfect closure. It is also advantageous to arrange the openings establishing communication between the pump-cylinder and the reservoir at such a height above the bottom of the reservoir that even when the brush is reversed with the bristles upward the openings are still below the liquid level so that even in this position liquid is able to pass into the cylinder of the pump. By this means the result is attained that in every position of the brush liquid can be discharged by the pump into the bristles and that the reservoir presents an air-tight closure to the exterior even when the outlet is open. The brush embodying the invention is therefore specially adapted for purposes wherein readily volatile liquids such as benzine or the like are employed as the moistening agent, such for example as cleaning brushes for typewriters, type and the like and also for purposes where, owing to difficulty of access to the object on which the brush is used, it is necessary to use the brush in various positions.

An embodiment of the invention is illustrated by way of example in the accompanying drawing.

1 is the body of the brush, the handle of which is made hollow so as to form a reservoir. A tube 3 or the like is inserted in the reservoir above the discharge opening 2 and communicates with the reservoir 1 through slots 5. An automatically closing valve 6 is provided for closing the discharge aperture; this valve is opened by exerting pressure on a press-button 7. In addition to the valve 6 for the aperture 2 there is arranged within the cylinder 3 a piston 8, which obturates the upper end of the cylinder and which when the valve 6 is closed, is located above the slots 5 in the piston cylinder 4, so that the cylinder is in communication with the reservoir. If the piston is depressed for the purpose of moving the valve 6 to a position to open the outlet 2 the slots 5 in the piston cylinder are covered, and the cylinder is cut off from the reservoir, so that the reservoir is hermetically closed when the outlet 2 is open. The piston 8 acts on the liquid that has entered the piston cylinder in the manner of the piston of a sprayer or syringe and sprays the liquid on to the bristles 10, a pad or the like, while on its return movement (and that of the valve 6 into closing position) it is able to draw in air from the atmosphere, which air passes through the slots 5 (when these are opened by the piston 8) into the reservoir 1 and replaces the liquid which flows from the reservoir into the cylinder, thus rendering such flow of liquid possible. For the purpose of hermetically closing the upper-end of the piston-cylinder one or more washers 9 of impermeable material are arranged between the piston 8 and the press-button 7. The reservoir can be filled through a filling aperture hermetically closed by means of a screw plug 11 or the like.

What is claimed is:—

1. A brush for wet brushing, comprising brushing means, a liquid reservoir upon said brush, and a force-pump in communication with said reservoir, having a restricted outlet, and adapted to force a column of liquid against its own weight in an inverted position of the brush into said brushing means.

2. A brush for wet brushing, comprising brushing means, a liquid reservoir upon said brush, a force-pump adapted to force a column of liquid against its own weight in an inverted position of the brush into said

- brushing means, said force-pump comprising a piston, a cylinder having a liquid outlet, and a valve controlling the passage of liquid through said outlet.
5. 3. A brush for wet brushing, comprising brushing means, a liquid reservoir upon said brush, a force-pump adapted to force a column of liquid against its own weight in an inverted position of the brush into said brushing means, said force-pump comprising a cylinder having a liquid-inlet and a valve controlled outlet, a piston, and a valve controlling the passage of liquid through said outlet, said piston operating to close said inlet in the initial part of its pressure-stroke.
10. 4. A brush for wet brushing, comprising brushing means, a liquid reservoir upon said brush, and a force-pump adapted to force a column of liquid against its own weight in an inverted position of the brush into said brushing means, said force-pump comprising a piston, a cylinder having a liquid outlet therein and a valve controlling the 20 passage of liquid through said outlet, said valve having its movements controlled by said piston.
15. 5. A brush for wet brushing, comprising a brushing means, a liquid reservoir upon said brush, and a force-pump adapted to force a column of liquid against its own weight in an inverted position of the brush into said brushing means, said pump comprising a cylinder located in said reservoir, and a piston in said cylinder, said cylinder having an inlet thereto from said reservoir, and a valve-controlled liquid outlet.
20. 6. A brush for wet brushing, comprising a brushing means, a liquid reservoir upon said brush, and a force-pump adapted to force a column of liquid against its own weight in an inverted position of the brush into said brushing means, said pump comprising a cylinder located in said reservoir, and a piston in said cylinder, said cylinder having an inlet thereto from said reservoir, and a valve-controlled liquid outlet. 25
7. A brush for wet brushing, comprising a brushing means, a liquid reservoir upon said brush, and a force-pump adapted to force a column of liquid against its own weight in an inverted position of the brush into said brushing means, said pump comprising a cylinder located in said reservoir and passing entirely through said reservoir, and a piston in said cylinder, said cylinder having an inlet thereto from said reservoir, and a valve-controlled liquid outlet. 30
35. In testimony whereof I have signed my name to this specification in the presence of two subscribing witnesses.
